(57) **CLAIM**

The ornamental design for a hot melt adhesive hose hanger, as shown and described.

DESCRIPTION

FIG. 1 is a front isometric view of the hot melt adhesive hose hanger.

FIG. 2 is a front view of the hot melt adhesive hose hanger, the rear view being identical to the front view.

FIG. 3 is a right side view of the hot melt adhesive hose hanger, the left side view being identical to the right side view.

FIG. 4 is a top view of the hot melt adhesive hose hanger; and,

FIG. 5 is a bottom view of the hot melt adhesive hose hanger. The areas inside of the dashed lines in FIGS. 1, 3 and 5 form no part of the claim.
